UNITED STATES PATENT OFFICE.

EUGENE S. MANNY, OF MONTREAL, QUEBEC, CANADA.

HOT-WATER BOILER.

SPECIFICATION forming part of Letters Patent No. 388,893, dated September 4, 1888.

Application filed July 14, 1888 Serial No. 279,995. (No model.)

To all whom it may concern:

Be it known that I, EUGENE SOLOMON MANNY, a citizen of the Dominion of Canada, and residing in the city and district of Montreal and Province of Quebec, Canada, have invented certain new and useful Improvements in Hot-Water Boilers; and I do hereby declare that the following is a full, clear, and exact description of the same, such as will enable others skilled in the art to which it appertains to make and use the same.

My invention has reference to a hot-water boiler in which the return-water, instead of going into the boiler at its lower portion, enters by the top and descends within the boiler, thus avoiding a disadvantage met with in all the hot-water boilers receiving the return-water at the bottom—that is, the cooling of the coal next to the partition where the cold water enters, and thus this coal does not burn, or burns very imperfectly, as it is kept in a black state most of the time.

The object of my invention is to provide a hot-water boiler having the advantages of not cooling the coal in the fire-box, and of being compact, cheap, and quick of action.

Referring to the drawings, similar letters refer to similar parts throughout the several views.

Figure 1 is a front elevation shown half in section, and the upper portion shows a section through *aa* of Fig. 2. Fig. 2 is a section through *x x' x'' x'''*, and Fig. 3 is a plan view taken at *yy*.

As there is nothing new about the fire-box, grating, or ash-pan it is useless to describe them. However, around the fire-box *A* is placed a water-leg, *B*, the object of which will be explained hereinafter. On top of this water-leg, which is rectangular, Fig. 3, is placed a partly-cylindrical portion, *C*. In this latter is placed the two partitions *D* and *E*, these serving to support the water-flues *F*, in which are placed horizontal partitions *G*. Consequently, the flames and hot gases ascending from the fire-box *A* strike directly on the partition *E* and water-flues *F* and *O*, thus heating them to a very high temperature, the smoke and gases escaping through the opening *H*. On the front *I* of the cylindrical portion *C* is placed a cast-iron front end, *J*, provided with the doors *K* and fire-box door *L*. Now, the action of my hot-water boiler is very simple. The return-water flows in at *M M'*, as shown by arrows, and thence through the

rectangular passage *N*, where, continuing to go downward, a certain portion passes through the water-flues *O*, which are larger than those for the hot water and designated by *F*; but they are kept in position at one end by the partition *D*, and at the other they are inserted into the partition of the passage *N*. This return-water, however, gets heated as it descends, and when it enters the water-leg *B* at *P* it is comparatively hot, so that it does not cool the burning coal placed next to the partition of the water-leg opposite the entrance *P*. The water then runs around the fire-box *A* in the water-leg *B*, as shown by arrows, and then ascends through the aperture *Q* into the space *R*, where it ascends, a certain portion of the heated water going through the partitioned flues *F*, so that by the time it passes out into the distribution-pipes *T T'*, as indicated by arrows, it has reached a very high temperature. The water-leg *B* is smaller in section opposite the fire-box door *L*—that is, there is a depression in the casting, as shown at *V* in Figs. 2 and 3. Moreover, the water-leg *B* is partitioned off between the inlet *P* and the outlet *Q*, the object of which is to stop the direct passage of a certain portion of the return-water into the outlet *Q*.

As can be seen, the main advantages of my hot-water boiler are the not-cooling action of the return-water on the hot coal in the fire-box opposite its inlet; also, it possesses a very quick action and is cheap of manufacture.

The partition *D* can be left out, if desired. In that case the door *K* serves to give access to the water-flues and clean the space between them.

Having described my invention, what I claim, and desire to secure by Letters Patent, is—

In a hot-water boiler of the class described, the combination, with the top returning-pipes, *M M'*, passage *N*, and water-flues *O* and *F*, with the water-leg *B*, the openings *P* and *Q*, the partitions *D E*, and fire-box *A*, substantially as described, and for the purposes set forth.

In testimony whereof I have affixed my signature in presence of the two subscribed witnesses.

E. S. MANNY.

In presence of—
J. D. DUCHORNE,
CLOVIS LEDUC.
